UNITED STATES PATENT OFFICE.

GEORGE D. MACBETH, OF PITTSBURGH, PENNSYLVANIA.

DESIGN FOR AN AUTOMOBILE HEADLIGHT LENS.

Application filed June 1, 1926. Serial No. 17,901. Term of patent 14 years.

To all whom it may concern:

Be it known that I, GEORGE D. MACBETH, a citizen of the United States, residing at Pittsburgh, in the county of Allegheny and State of Pennsylvania, have invented a new, original, and ornamental Design for Automobile Headlight Lenses, of which the following is a specification, reference being made to the accompanying drawing, forming a part thereof.

Fig. 1 of the drawing is a front view of the lens; Fig. 2 a rear view; and Figs. 3 and 4 sectional views taken, respectively, on the lines III—III and IV—IV, Fig. 2.

I claim:

The ornamental design for an automobile headlight lens, as shown.

GEORGE D. MACBETH.
